US00D865256S

(12) **United States Design Patent** (10) Patent No.: **US D865,256 S**
(45) Date of Patent: **** Oct. 29, 2019**

(54) **SOLAR LAMP**

(71) Applicant: **Shenzhen Moersen Lighting Technology Co., Ltd.**, Shenzhen (CN)

(72) Inventor: **Chen Zou**, Shenzhen (CN)

(73) Assignee: **Shenzhen Moersen Lighting Technology Co., Ltd.**, Shenzhen (CN)

(**) Term: **15 Years**

(21) Appl. No.: **29/671,831**

(22) Filed: **Nov. 30, 2018**

(51) LOC (12) Cl. **26-05**

(52) U.S. Cl.

USPC **D26/71**

(58) **Field of Classification Search**

USPC D26/71, 72, 76, 78, 88, 89, 118

See application file for complete search history.

(57) **CLAIM**

The ornamental design for the solar lamp, as shown and described.

DESCRIPTION

FIG. 1 is a first perspective view of the solar lamp showing the claimed new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown on the drawings represent portions of the solar lamp that form no part of the claimed design.
